UNITED STATES PATENT OFFICE

138,969

DESIGN FOR A COMBINED DISK GRINDER AND SURFACER

Alfred J. Bowen, Beloit, Wis.

Application September 23, 1943, Serial No. 111,196

Term of patent 14 years

(Cl. D37—1)

To all whom it may concern:

Be it known that I, Alfred J. Bowen, a citizen of the United States, residing at Beloit, in the county of Rock and State of Wisconsin, have invented a new, original, and ornamental Design for a Combined Disk Grinder and Surfacer, of which the following is a specification, reference being had to the accompanying drawings, forming part thereof.

Fig. 1 is a front perspective view of a combined disk grinder and surfacer showing my new design; and

Fig. 2 is an end elevational view thereof taken from the right of Fig. 1.

I claim:

The ornamental design for a combined disk grinder and surfacer, as shown.

ALFRED J. BOWEN.
